(57) **CLAIM**

The ornamental design for a jet regulator, as shown and described.

DESCRIPTION

FIG. 1 is a top plan view of a jet regulator in accordance with our design;

FIG. 2 is a top, front perspective view thereof;

FIG. 3 is top, front perspective view thereof including section lines that indicate the section planes where the partial section view shown in FIG. 4 is taken;

FIG. 4 is a partial cross-sectional view similar to FIG. 2 that shows the depth of certain features;

FIG. 5 is a front elevational view thereof;

FIG. 6 is a right side elevational view thereof;

FIG. 7 is a rear side elevational view thereof;

FIG. 8 is a left side elevational view thereof;

FIG. 9 is a bottom, rear perspective view thereof; and,

FIG. 10 is a bottom plan view thereof.

The broken lines represent the boundaries of portions of the jet regulator that form no part of the claimed design.

1 Claim, 10 Drawing Sheets
